HARRY S. LEE, AMOS E. CHAFFEE, AND FRED MILLARD, OF PLYMOUTH, MICHIGAN; SAID CHAFFEE AND SAID MILLARD ASSIGNEES OF THEIR ENTIRE RIGHT TO THE SAID LEE.

PERMANENT-MOLD CONSTRUCTION.

Application filed February 21, 1925. Serial No. 10,630.

To all whom it may concern:

Be it known that we, HARRY S. LEE, AMOS E. CHAFFEE, and FRED MILLARD, citizens of the United States, residing at Plymouth, in the county of Wayne and State of Michigan, have invented certain new and useful Improvements in Permanent-Mold Construction, of which the following is a specification.

10 This invention relates to mold construction, and more particularly pertains to molds provided with means whereby the meeting faces of the molds are automatically adjusted so that the same will remain perfectly parallel, and therefore always meet.

With all molds, and especially so with molds that have a greater relative length than width, it is the tendency of them to bow when heated. These molds are subjected to very high temperatures, as the metal which is poured therein has a temperature of approximately 1700 to 2000 degrees Fahrenheit. This causes the face of the mold to become extremely hot while the rear of the mold has a less temperature. This causes the mold to expand and when the mold is rigidly secured to the carrier or support this expansion will cause the mold to bow out. To overcome this tendency it is customary to only secure the mold to the support at one point thus allowing for expansion, in all directions parallel to the face of the mold. However, it is found that the face of the mold expands at a greater rate than the rear of the mold which is more remote from the casting, due to the fact of the difference in temperature. This difference in expansion tends to bow out the mold or warp the same and it is found that the faces of the molds are not parallel, and prevents the mold from forming a perfect joint.

Our invention pertains to means for controlling this warping or bowing action in such a manner as to counteract the tendency of the mold to bow due to the difference in the rate of expansion between the face of the mold and the rear portion of the mold.

In the drawings:

Fig. 1 is an elevational view of the face of a mold which has a considerable length as compared with the width.

Fig. 2 is a vertical section on the line 2-2 of Fig. 1.

Fig. 3 is an enlarged detail of one

end of the mold showing the die expanded. 55

Fig. 4 is an enlarged modified detail of one end of the mold showing separate regulatable means for controlling this expansion.

Fig. 5 is a view similar to Fig. 4, but showing the die expanded. 60

This mold consists of two parts—a subhead *a* and a die *b*. This die is provided with a molding cavity *c* and the hot metal is poured therein. In the drawings I have shown only one half of the completed mold as the other half is an exact duplicate and will be abutted up against this half and properly located by the dowel pins *d*. These dies are so machined and finished that they will abut each other and tightly fit against each other to prevent any leakage of the molten metal from between the abutting faces of the dies. Obviously the molds can be of any shape, large or small and we do not limit ourselves to the specific form of mold shown in the drawings. 70

To counteract the tendency of the die to bow when heated during the time when the casting is poured, we provide the inclined bearing faces *e* on the subhead and the bearing faces *f* on the die which are complementary to the bearing faces on the subhead. The die is secured to the subhead at an intermediate point by the screws or bolts *g*, and the ends of the die are secured to the 80 subhead by the screws *h* but the die is provided with an elongated slot *i* which permits the ends of the die to freely slide with respect to the subhead. As the die expands in a direction parallel to the face of the die 85 due to the change in temperature the inclined bearing face of the die will ride up the inclined bearing face carried by the subhead, as shown in Fig. 3, and this will force the free ends of the die toward each other 90 to counteract the tendency of the die to bow outwardly. This will maintain the face of the die in substantially parallel relation with the face of the mating die and prevent leakage of the molten metal. Obviously this 95 control means could be located to correct warping or bowing from side to side as well as lengthwise.

In Figs. 4 and 5, we show a modified form of construction in which the expansion plug *k* is inserted in the subhead and projects through the inclined bearing face. A screw *m* is backed up against the rear of the ex-

pansion plug and by screwing the same in or out the expansion plug may be adjusted. This expansion plug may be formed of any metal that has a greater ratio of expansion 5 than the metal of the mold, such as aluminum, brass, bronze or steel plugs. This plug when heated expands at a greater rate than the subhead, and as shown in Fig. 5, this bears against this inclined bearing face carried 10 by the die, and exerts a pressure transversely of the die at the free ends to counteract the tendency of the die to bow. With such an expansion plug a better control of the mold may be had, as this expansion plug 15 may be adjusted mechanically and by using plugs of different material the same may expand at a greater or less rate. This gives us an automatic thermostatic control of the mold in addition to the mechanical control 20 so that the machined faces of the molds remain perfectly parallel. The location and number of these expansion plugs depend upon the size and shape of the mold.

Such a control is especially desirable 25 when using molds which have a much greater dimension in one direction, but such a control can be used with molds of any size or shape, and in fact we are using such a construction in all of our molds as there is 30 always a slight tendency of the molds to bow, no matter what their size and shape is.

This application is directed to the automatic control of mold section distortion in permanent molds, regardless of the direction 35 of bowing or distortion. It is more particularly directed to the accomplishment of this purpose by means of interposing a mechanical element for furnishing a countervailing effort tending to neutralize these 40 distortions. There are claims involved in this case which refer to the use of a thermally responsive element in connection with the special mechanical design for affording the countervailing effort. However, the 45 particular principle of counteracting the distortion of the mold section by a thermally responsive element is not broadly claimed in this application except so far as it may be covered by the broad claims for 50 the automatic control of the distortion. The utilization broadly of thermally responsive elements to effect this control is considered a separate invention and is claimed in application Serial No. 39,053, filed June 23, 55 1925.

What we claim is:

1. A mold, having in combination a support, a die secured thereto and permitted to expand and tending to bow when heated, and automatic means for applying pressure transversely of the die when the same expands to counteract the tendency of the die to bow as the result of such expansion. 60

2. A mold, having in combination, a support, a die secured thereto and permitted to

expand and tending to bow when heated, and regulatable means for applying pressure transversely of the die when the same expands to counteract the tendency of the die to bow as the result of such expansion. 70

3. A mold, having in combination, a support, a die secured thereto at an intermediate point and permitted to expand and tending to bow when heated, and automatic means for applying pressure at the ends of the die and transversely of the die when the same expands to counteract the tendency of the die to bow under such expansion. 75

4. A mold, having in combination, a support, provided with one or more inclined bearing faces near the outside edge, and a die secured near the center to said support and provided with inclined bearing faces near the ends complementary to and engaging the inclined faces on the support, said die permitted to expand and tending to bow when heated, thereby causing the inclined faces on the die to ride up the inclined faces of the support, whereby pressure is applied at the ends of the die and transversely thereof to counteract the tendency of the die to bow when heated and expanded. 80

5. A mold, having in combination, a support provided with one or more inclined bearing faces near the outside edge, adjustable means for correctly positioning said bearing face, and a die secured near the center to said support and provided with inclined bearing faces near the ends complementary to and engaging the adjustable inclined faces on the support, said die permitted to expand and tending to bow when heated, whereby the inclined faces on the die are caused to ride up the inclined faces on the support, to apply a force near the end of the die transversely thereof to counteract the tendency of the die to bow when heated and expanded. 95

6. A mold, having in combination, a support provided with one or more inclined bearing faces near the outside edges, thermostatically controlled means for positioning the said bearing faces, and a die secured near the center to said support and provided with inclined bearing faces near the ends complementary to and engaging the inclined faces on the support, said die permitted to expand and tending to bow when heated, whereby the inclined faces on the die are caused to ride up to the thermostatically controlled inclined faces on the support to counteract the tendency of the die to bow when heated and expanded. 100

7. In a mold, the combination of a die which expands and tends to bow when heated, and automatic means for controlling the tendency of said die to bow. 115

8. In a mold, the combination of a die which expands and tends to bow when heat- 120

130

ed, and means for automatically applying pressure transversely of said die to counteract the tendency of said die to bow.

9. In a mold, the combination of a die which is caused to be heated to a higher temperature on one side than on the other and thereby expanded unequally thus tending to bow the die, and automatic means for correcting the tendency of said die to bow.

10. In a mold, the combination of a die

which when heated expands in a direction parallel to the plane of the die and tends to bow, and means for automatically applying a pressure transversely of the plane of said die to counteract the tendency of said die to bow.

In testimony whereof we have affixed our signatures.

HARRY S. LEE.
